IMPRINT MACHINE

Clement Lee Downey, Hannibal, Mo., assignor to
 Johnson Fare Box Company, Chicago, Ill., a
 corporation of Delaware

Application May 29, 1948, Serial No. 30,097

7 Claims. (Cl. 101—37)

1

This invention relates to an imprinting machine, and more particularly to a machine for imprinting identification marks upon packaged money.

One of the objects of the invention is the provision of a device whereby rouleaux or coin-charged packages, may be neatly imprinted with the identifying mark of a bank or the like, at a rapid rate.

Another object is to include, in a machine of this type, means for rendering the device inoperative after a predetermined number of rouleaux or other packages have passed therethrough.

A further object is to provide a machine of the character stated which may be adapted for imprinting rouleaux of various diameters and lengths, that is to say, wrapped coins of various denominations in any monetary system, as well as other commodities of various shapes and sizes.

Another object of the invention is to provide an imprinting machine which is simple, reliable, and free from the need of frequent attention or servicing.

Another object is to provide a machine of the character stated, which easily and quickly may be converted to process articles other than packaged coins, as may be desired.

The foregoing and other objects and advantages are attained by the means described herein and illustrated upon the accompanying drawings, in which:

Fig. 1 is a side elevational view of the imprinting machine showing the gauges set for imprinting rouleaux of dimes, parts of the machine being broken away for clarity of disclosure.

Fig. 2 is a cross sectional view taken on line 2—2 of Fig. 1, part of the gauge plate being broken away.

Fig. 3 is a fragmentary cross sectional view taken on line 3—3 of Fig. 1.

Fig. 4 is a fragmentary cross sectional view taken on line 4—4 of Fig. 1.

Fig. 5 is a fragmentary and elevational view taken on line 5—5 of Fig. 1.

Fig. 6 is an enlarged cross sectional view of a clutch cam lever, which forms part of the invention, taken on line 6—6 of Fig. 4.

Fig. 7 is a fragmentary perspective view, showing means for adjusting the device for various denominations of coins.

Fig. 8 is a detailed perspective view of a bell crank and gear segment which forms part of the invention.

Fig. 9 is a front elevational view of the rouleau counter, taken on line 9—9 of Fig. 2.

Fig. 10 is an end elevational view of the rouleau counter, taken on line 10—10 of Fig. 9.

Fig. 11 is an enlarged perspective view of the counter setting shaft and latch.

For a proper understanding of the present invention, it is necessary to appreciate that the machine disclosed herein is adapted to imprint an identifying mark upon packaged money and the like, such as rouleaux. The machine is adjustable to receive rouleaux of varying lengths and imprint a circumferential mark between the ends thereof.

Ordinarily, coin wrappers have denominational marks, such as "pennies," "nickels," and the like, printed longitudinally of the roll of coins, substantially centrally thereof. The device of the present invention contemplates the use of coin wrappers having their denominational marks near either or both ends of the rouleaux, in order to provide a blank space circumferentially of the roll of coins, at the approximate center portion thereof, for imprinting an identifying mark thereupon. However, the device may be adapted to imprint a mark at any point between the ends of a rouleau or the like.

Referring to Fig. 1, the imprint machine is shown supported upon a base plate 15, which may in turn be supported by means of the upright post 16 of a suitable pedestal, the upper end of said post being disposed within the hub 18 of the base plate and fixed therein by suitable means, such as the pin 19. The base plate 15 may be of any suitable configuration, but that shown in Fig. 2 is preferred because of its compactness and neat appearance.

Fixed to the base plate 15, upon its longitudinal axis, is the upright irregularly shaped turret bracket 20, vertically bored to receive the rotatable turret shaft 21. The turret bracket 20 may be provided with flanges 22 apertured to receive screws 23 threaded into the base plate 15, as a means of fixing the turret bracket to the base plate.

Keyed to the upper end of the turret shaft 21 is the coin turret 24, which may be in two parts: a body 25, and a cap 26, as shown in Fig. 1, said cap being detachably fixed to the body by means of screws 28. Near its lower extremity, the turret shaft 21 may be provided with a fixed collar 29, the lower face of which may abut the upper race of a thrust bearing 30, the collar and thrust bearing being disposed within a counter-bore 31 provided for that purpose in the lower

part of the turret bracket 20. The coin turret 24 is also supported by means of a hub 32 depending from the inner face of the turret cap 26 and abutting the upper face 33 of the turret bracket 20, this support being in addition to the anti-friction support indicated at 29, 39, and 34.

The coin turret 24 is rotated by means of a miter gear 34 keyed to the turret shaft 21, said gear being in mesh with a mating miter gear 35 keyed to a horizontal clutch shaft 36, which takes its bearing at one end in the upstanding turret bracket portion 38 and at its opposite end in the clutch shaft housing 39. It will be noted that the turret bracket is cut away, as at 40-40, in order to provide clearance for the mating miter gears 34-35. The clutch shaft housing may comprise an upright substantially flat plate provided with outwardly extending feet 37, apertured for mounting upon the base plate 15 by means of screws 47, transversely of the longitudinal axis of the said base plate.

A free-running gear 41 is mounted upon the clutch shaft 36, between the housing 39 and the turret bracket 38, and is constantly driven by the meshing pinion 42, which in turn is driven by the motor 43 through the worm 44 and worm gear 45, as shown in Fig. 1. The motor, as indicated, may be supported from the lower face of the base plate 15, and may be provided with suitable gear reduction means, as indicated by the gear box 46.

The turret 24 is provided with a series of vertical rouleau wells 48, equally spaced upon a radius concentric with and adjacent to the periphery of the turret. The rouleau wells 48 are of sufficient diameter to loosely receive wrapped coins of the larger diameters for imprinting, such as half-dollars of the U. S. monetary system. Rouleaux are held in a vertical position in the wells 48, supported by the gauge plate 49, the intermediate portion of the rouleaux being in substantial alignment with openings 50 milled or otherwise provided in the outer wall of the turret body 25. An opening 59 is provided for each rouleau well 48. Since rouleaux containing standard amounts of coins vary in length according to the denomination of the coins, provision has been made for adjusting the gauge plate 49 in order to substantially centralize each denomination of rouleau with the turret wall openings 50. The function of the turret wall openings will be disclosed later.

A second upstanding portion of the turret bracket 20, indicated at 51 in Fig. 7, is provided with opposed vertical parallel slots 52. The substantially circular gauge plate 49 is provided with a pair of depending lugs 53, spaced apart to permit a free sliding fit vertically upon the turret bracket portion 51. A plurality of pins 54, Figs. 1, 2, and 7, inwardly projecting from the depending lugs 53, are adapted to engage the turret bracket slots 52 in a sliding fit, thereby to guide the gauge plate in adjusting it to various elevations in accordance with the requirements of the rouleau denomination to be imprinted. Means for manually elevating the gauge plate 49 may be provided in the form of a setting lever 55, integrally or otherwise associated with the lever plate 56 which is removably attached to the outer faces of the gauge plate lugs 53, as by means of screws 58.

Means for maintaining the gauge plate 49 in a selectively adjusted position may be provided, such as a stop block 59, shown in Figs. 2 and 7. The stop block may be cylindrical in form, hav-

ing buttresses 60 of varying elevations projecting therefrom rotatably mounted upon a pin 57 pressed into a centrally apertured post 61 provided upon the base plate 15 adjacent the turret bracket 20. For ease in rotating the stop block 59, a knurled disc 62 may be fixed to the lower face thereof. Each buttress 60 is of a different elevation, one for each denomination of rouleau to be imprinted. The upper face of 10 the knurled stop-block disc 62 may carry indicia to indicate the various denominations of rouleaux to be acted upon, as shown at 63. The lower face of the disc 62 abuts the upper face of the post 61.

As shown in Fig. 7, the lower face 64 of a gauge plate lug 53 gravitationally abuts a selected stop block buttress 60. As will be understood, the elevation of each buttress 60 is calculated to position the rouleau of the selected denomination whereby the intermediate portion thereof is in substantial alignment with the turret wall openings 50. The drawings show the machine adjusted for imprinting a rouleau of dimes 67. In adjusting the machine, the operator of the device manually elevates the gauge plate, by means of the setting lever 55, to the point where the gauge block lug 53 clears the stop block, then manually rotates the stop block 59 until a buttress 60 of the desired denomination is disposed beneath the gauge block lug 53, then permits the said lug to come to rest upon the selected buttress. The depending rib 65 upon the gauge plate 49 is merely for reinforcing said gauge plate.

Rouleaux passing through the machine are imprinted by the rotatable printing roll 68, keyed to the upper end of the printing roll shaft 66 vertically mounted in the forwardly extending portion 69 of the substantially vertical rocker arm 70. The rocker arm is pivotally mounted upon the rocker shaft bracket 71, by means of the rocker shaft 72, horizontally mounted in the rocker shaft bracket, coplanar with, but at substantial right angles to, the clutch shaft 36. 45 Fixed to the hub 73 of the free-running gear 41 and rotatable therewith is the small miter gear 74, in mesh with a larger miter gear 75, mounted for rotation upon the rocker shaft 72. As shown in Fig. 3, the rear face of the miter gear 75 abuts 50 the forward face of the rocker arm 70. The large miter gear 75, driven by the small miter gear 74, drives a second small miter gear 76, keyed or pinned, as at 78, to the lower end of the printing roll shaft 66. The printing roll 68 55 may comprise a cylinder of suitable material, such as metal, plastic, or wood, having secured about its periphery a rubber or composition mat provided with the type matter to be imprinted upon the rouleaux. The rocker shaft bracket 71 60 may be mounted upon the base plate 15 by means of screws 77.

An arcuate depression 80, Figs. 1 and 2, is provided upon the outer turret wall for each rouleau well 48, the radius of said depressions being substantially that of the printing roll 68. Each turret wall opening 50 is substantially in the center of a depression 80, so that as the printing roll 68 is rotated, the printing surface thereon will contact the paper wrapper of the rouleau 67 in the well 48 through said wall opening. The rocker arm 70 may be provided with yielding means for maintaining the printing roll 68 in contact with that part of the rouleau 67 communicating with the printing roller through the opening 50. The yielding means may be in

the form of a tension spring 81, Fig. 1, having one end anchored to a post 82 provided upon the turret bracket upright 38, and its opposite end secured to the rocker arm 70, above the pivotal point.

Since the free-running gear 41 on shaft 36 is constantly rotating as long as the motor 43 is energized, the printing roll 68 is also in constant rotation through the miter gears 74, 75, and 76. Means for supplying ink to the printing roller 68 may be provided, such as an inking roller 68a, Fig. 1, mounted to contact the printing surface of the roller 68 and transfer ink thereto by frictional rotation therewith. The inking roller may be mounted on a shaft 68b, parallel with rocker shaft 66, the inking roller shaft 68b taking its bearing in extensions 68c provided on the rocker member 69.

For each rotation of the free-running gear 41, the turret 24 is rotated one-third of a revolution, through the medium of a novel clutch means clearly illustrated in Fig. 4. Abutting the flat face 83 of the gear 41 is a clutch carrier plate 84, also mounted for free-running upon the clutch shaft 36. The clutch carrier plate 84 carries a pivoted clutch trip lever 85, the inner face of which normally abuts the gear face 83, being held in contact therewith by yielding means, such as a leaf spring 86 fixed to the clutch carrier plate 84. As shown in Fig. 4, the clutch trip lever 85 extends radially from the carrier plate 84, being pivoted for movement to and from the gear face 83, the pivot means being indicated by the pin 88.

Abutting the clutch carrier plate 84 and keyed to the clutch shaft 36 is a four-tooth ratchet 89, actuated by the pawl 90 pivoted to the carrier plate 84, the ratchet key being indicated at 91. A clutch pin 92, driven into the gear 41 and slightly extending from the face 83 thereof in a position to contact the clutch trip lever 85, acts to drive the carrier plate 84 and its pawl 90 to rotate the clutch shaft 36 through the keyed-on ratchet 89. The clutch trip lever 85 is disengaged from the clutch pin 92 by means of a clutch cam block 93, having a beveled or inclined face 94, as shown in Fig. 6, said cam block being fixed to the inner face of the clutch shaft housing 39. As revealed in Fig. 4, the inclined face 94 of the clutch cam block is in the path of the outer end of the clutch trip lever 85 as it is moved by means of the constantly rotating gear 41. As the clutch trip lever is driven over the inclined cam face 94, it is raised out of contact with the clutch pin 92, and the carrier plate 84 returned to the starting position shown in Fig. 4, by suitable means, such as a spiral spring 95. This spring may be secured to the clutch shaft housing 39 by means of a pin 97 fixed to said housing, with the free end of the spring pinned to the clutch carrier plate 84, as at 87. In its return to starting position, the clutch carrier plate is stopped by means of a clutch trip lever stop 96 fixed to the clutch shaft housing 39, substantially 90° from the clutch cam block 93. In the exemplified form, the cam block 93 and the trip lever stop 96 are of substantially the same shape except for the inclined face 94 on the former. As illustrated upon Figs. 1 and 2, the members 93 and 96 are secured to the clutch shaft housing 39 by means of screws 98.

Thus it will be seen that as the clutch pin 92, carried by the constantly rotating free-running gear 41, engages the clutch trip lever 85, this motion is translated to the clutch shaft 36 through the pawl 90 and the keyed-on ratchet 89. Rotation of the shaft 36 ceases when the clutch trip

lever 85 passes over the cam 94, the shaft 36 having made one-quarter revolution. The pin 92 continues to travel in its orbit and upon each revolution thereof the clutch shaft 36 is rotated 90°. The motion of the shaft 36 is translated to the coin turret 24, through the meshing miter gears 34 and 35.

While any suitable ratio between the free-running gear 41 and the coin turret 24 may be used, the ratio in the exemplified device is three to one. The ratio between the meshing miter gears 35 and 34 is three-quarters to one, since the gear 35 has twenty-four teeth and the gear 34 has eighteen teeth. The timing of the intermittent rotation of the coin turret 24 in the instant case has been set at twelve seconds per revolution, each movement or $\frac{1}{3}$ revolution requiring one second followed by a pause of three seconds. Figs. 1 and 2 show a rouleau 67 in a rouleau well 48 being stamped or imprinted by the constantly rotating printing roll 68, through the turret wall opening 50 during a three-second pause.

As shown in Fig. 2, the coin turret is provided with three rouleau wells 48, one well being in each of the positions marked A, B, and C during the three-second pause. A complete cycle of the imprinting operation is as follows: A rouleau is dropped by manual or mechanical means into the rouleau well at station A. The rouleau is moved to station B where it is imprinted during the three-second pause by the printing roll 68, and another rouleau is dropped into the well at station A. The first rouleau is then carried to station C, having been suitably imprinted, and is gravitationally discharged through openings 98 and 99, Fig. 1, provided in the gauge plate 49 and the base plate 15, respectively, into a bag or other receptacle, while the second rouleau is carried to station B for imprinting and a third rouleau dropped into the turret at station A. This procedure is continued until the desired number of rouleaux of one denomination have been imprinted. Means for selectively limiting the machine to a predetermined number of rouleaux passing through the well at station C may be provided, such as the rouleau counter shown in Figs. 9 and 10, later to be described.

A tubular guide or chute may be provided between the gauge plate aperture 98 and the base plate aperture 99, although this is not necessary, since the said apertures are in vertical alignment with the rouleau well 48 at station C. Means for supporting standard canvas coin bags for receiving imprinted rouleaux may be provided, such as hooks 100 secured to the lower face of the base plate 15.

Means for tripping the printing roll 68 out of proximity with the turret 24 during the time when the turret is in motion have been provided, said means being synchronized with movement of the turret, as clearly depicted in Fig. 3. Upon the hub 73 of the free-running gear 41 is a cam 101, concentric with the said gear and extending substantially 90° about its axis. Pivoted to the forward end of the rocker shaft bracket 71 is the substantially horizontal cam trip arm 102, the pivot means being the pin 103, which takes a bearing transversely of the said rocker shaft bracket, as shown in Figs. 1 and 2. Opposite the pivot end, the cam trip arm 102, Fig. 3, carries a trip roller 104, rotatably mounted upon an inwardly extending finger 105 of the cam trip arm. The trip roller 104 normally rests freely upon a ledge 106 laterally extending

from the lower portion of the rocker arm 70. Substantially midway of the cam trip arm 102 and upstanding therefrom, in the path of the gear hub cam 101, is the triangular lug 108. The cam 101 is timed to strike the lug 108 approximately at the moment when the clutch pin 92 engages the clutch trip lever 85 on the opposite side of the free-running gear 41, the camming action and the clutch engagement being synchronized to operate for substantially one second of time. Thus it will be seen that as the cam trip arm 102 is depressed by the action of the cam 101, the trip roller 104 will cause the rocker arm 70 to move about its pivot 72, thereby tripping the printing roller 68 laterally out of proximity with the coin turret 24 during that period of time when the turret is being rotated $\frac{1}{3}$ of a revolution. After the cam 101 has passed over the trip arm lug 108, the printing roll is moved to its printing position by means of the spring 81 attached to the rocker arm 70, as shown in Fig. 1.

During the tripping of the rocker arm 70, the miter gear 76 remains in mesh with the miter gear 75, since the last named gear takes its bearing on the rocker shaft 72 upon which the rocker arm 70 is pivoted.

Means for arresting the momentum of the turret 24 in its intermittent movement have been provided for stopping the turret with its rouleau wells in alignment with stations A, B, and C. This is especially important regarding station B, since the turret wall opening 50 must line up with the printing roll 68 so that the latter will properly imprint the rouleau 67 in the well 49. It is also important that the coin turret be stopped with a rouleau well 48 in alignment with the gauge plate aperture 98 and base plate aperture 99, in order that the imprinted rouleau in the well at station C may be discharged there-through.

The momentum arresting means previously referred to is a clutch brake, illustrated clearly in Fig. 5. As shown therein, the clutch brake comprises a disc 109, keyed as at 110 to the outer end of the clutch shaft 36. The periphery of the brake disc 109 is provided with a series of arcuate notches 112, spaced at 90° intervals. As illustrated, the clutch brake disc, disposed against the outer face of the clutch shaft housing 39, is rotatable only when the clutch mechanism shown in Fig. 4 rotates the shaft 36. A brake arm 113 is pivoted at one end to the clutch shaft housing 39, and is provided at its opposite end with a freely rotatable roller 114, adapted to yieldingly engage an arcuate notch 112 in the brake disc. As indicated, the brake arm 113 and the base plate 15 may be socketed, as at 115 and 116, respectively, to receive a compression spring 118, which constantly urges the brake arm 113 with its roller 114 toward the periphery of the brake disc 109. The brake arm pivot is indicated at 119.

It will thus be seen that as the clutch mechanism operates to rotate the shaft 36 for $\frac{1}{4}$ revolution, any momentum which might be generated upon the release of the clutch pin 92 by the clutch trip lever 85, Fig. 4, is effectively arrested by the clutch brake means illustrated in Fig. 5. As the keyed-on brake disc is rotated by the clutch shaft 36, the brake roller 114 disengages the brake disc notch 112 with which it is engaged, and engages the following notch 112, thereby to arrest any further movement of the shaft 36 with its cooperating gears and coin

turret. The brake roller 114 always tracks upon the peripheral edge of the brake disc 109 as the disc is rotated.

Since rouleaux of various denominations are of different diameters, means for yieldingly maintaining the rouleaux in contact with the printing roll 68 have been provided, as illustrated in Figs. 1 and 2. The upstanding central portion 120 of the turret bracket 20, near its upper terminus, has been provided with horizontal slideways 121, Figs. 1 and 2, one on each side of the turret bracket. A substantially U-shaped platen pressure bar 122 is mounted for reciprocation in the slideways 121. A pair of freely rotatable pressure rollers 123 are mounted in side-by-side relation in the connecting leg of the U-shaped platen pressure bar 122. The pressure rollers 123 normally project into the area of station B, urged in the direction of the printing roll 68 by the spring loaded bell crank 124, pivoted at 125, Fig. 1, to the turret bracket portion 120.

As detailed in Fig. 3, the bell crank 124 is saddle-like in structure, and upon one side is provided with a depending gear segment 126, the function of which will be disclosed later. The substantially vertical arms 128 and 129 of the bell crank which freely embrace the turret bracket portion 120, are each provided with a slot 130 for engaging the free ends of a pin 131 transversely disposed through the legs of the U-shaped platen pressure bar. A compression spring 132 is seated in the bottom of a vertical recess 133 provided in the turret bracket between the bracket portions 51 and 120. A guide pin 134, having a head 135, is embraced by the spring 132, the said head being thereby urged into contact with the lower face of the connecting portion 136 of the bell crank 124. The action of the compression spring 132 is to force the bell crank portion 136 upwardly, causing the vertical arms 128 and 129 to move to the left, as viewed in Fig. 1, by reason of the pivotal connection 125. As the bell crank arms 128 and 129 are thus moved to the left, the platen pressure bar 122 is moved to the left, placing the pressure rollers 123 into yielding contact with the rouleau 67, thereby to urge the rouleau into contact with the printing surface of the rotating printing roll 68. The rouleau, being thus backed up by the pressure rollers 123, is caused to rotate by the action of the rotating printing roll 68, while the rouleau circumferentially receives an inked impression from the printing roll.

As shown in Fig. 1, an elongated horizontal slot 138 is provided transversely of the slideways 121, through which the platen pressure bar pin 131 is guided as the platen pressure bar 122 is reciprocated in the slideways by means of the bell crank 124.

The guide pin head 135 may be provided with a spherical radius, and the lower face of the bell crank portion 136 may be provided with a co-operating seat 141, as a means of precluding side-wise movement of the guide pin 134 as the bell crank 124 is actuated.

At the end of the three-second period during which the rouleau 67 is being imprinted, the rocker arm 70, carrying the rotating printing roller 68, is tripped by the means hereinbefore described. As the printing roller is thus tripped to the left, as viewed in Fig. 1, the rocker arm 70 carries with it the rack connecting bar 139, indicated in Figs. 1, 2, and 3. The upper surface of one end of the connecting bar is provided with

rack teeth 140, which are in mesh with the teeth of the depending bell crank gear segment 126, as shown in Fig. 1. The rack connecting bar is supported for horizontal reciprocation by suitable means, such as the screws 142 and 143, the former threaded into the rear face of the turret bracket 20, the latter threaded into the rear face of the rocker arm 70. Elongated slots 144 and 145 have been provided adjacent each end of the rack connecting bar 139 for the insertion therethrough of the supporting screws 142 and 143 respectively.

As the rack connecting bar 139 is thus carried to the left by the rocker arm 70, the rack teeth 140, in mesh with the bell crank gear segment 126, act to move the bell crank arms 128 and 129 to the right, carrying the platen pressure bar 122 to the right to release the rouleau 67 from contact with the pressure rollers 123. The tripping of the printing roller 68 and the releasing of the rouleau from the pressure of the platen pressure bar 122 are, of course, synchronized with the movement of the coin turret 24 as $\frac{1}{2}$ of the cycle is completed. Thus, while a rouleau is being carried from station A to station B, the rocker arm 70 is in tripped position and the platen pressure bar 122 is in retracted position. When the coin turret comes to rest, the printing roller 68 is returned to its operative position by the tension spring 81, while the pressure rollers 123 are advanced to contact and support the rouleau against the force of the compression spring 132.

Since rouleaux vary in diameter according to denomination, the elongated slots 144 and 145 in the rack connecting bar 139 permit the platen pressure bar to act upon rouleaux of any diameter with substantially equal pressure upon the rouleaux. The elongated slots 144 and 145 therefore act as a compensating agent in equalizing the pressure between the printing roller 68 and the pressure rollers 123 upon the rouleau at station B, regardless of the rouleau diameter.

The two rollers 123, by virtue of their side-by-side relation, serve to centralize the rouleau 67 in the rouleau well 48 at station B against the printing roller 68, the rollers 123 contacting the rouleau at opposite sides of the center line which bisects the rouleau at the printing roller contact point.

The coin turret 24 may be bodily removed from the turret shaft 21 and replaced with a turret of a different type, as for instance a paper or note currency turret. For this purpose, releasing means may be provided, such as the connecting bar release lever 146, shown in Fig. 1. This release lever, pivoted to the turret bracket 20 near the lower end thereof at 148, is substantially L-shaped, having the vertical arm 149 in abutting contact with an end face of the rack connecting bar 139. A lifting tab 150, extending beyond the perimeter of the base plate 15, may be provided upon the horizontal arm 151 of the release lever. Lifting the tab 150 will cause the rack connecting bar 139 to move to the left, tripping the printing roller 68 and retracting the platen pressure bar 122. After removal of the turret lock nut 152, the turret 24 may then be removed bodily from the shaft 21 and another type of turret placed thereon.

Means for selectively limiting the imprinted packages to a predetermined number may be provided, as hereinbefore related. Figs. 2, 9, and 10 delineate a package counter forming a part of the present invention. The counter comprises an upright assembly plate 153 with its component parts, including a cut-off switch 154, 75

mounted thereon. The assembly plate 153 is provided with an outwardly extending foot member 156 to form a base for anchoring the said assembly plate 153 to the base plate 15 by means of screws 155. The assembly plate is mounted in angular relation to the longitudinal axis of the base plate 15, the inner face being substantially coplanar with the periphery of the coin turret 24, and tangent to the rouleau well at station C.

Slidably mounted for horizontal reciprocation upon the top face of the counter assembly plate 153 is the counting pawl slide 156', provided with a laterally extending counting finger 158 which extends into the area of station C, Fig. 2, between the lower face of the turret 24 and the upper face of the base plate 15. The counting pawl slide 156, as shown in Fig. 10, may be U-shaped in cross section, inverted upon a track 159 provided by rabbeting the upper edge of the assembly plate 153. The counting pawl slide is held against displacement by means of guide pins 160 and 161 which traverse said slide, the pins engaging the elongated slots 162 provided in the track 159. The guide pin 160 also serves as a pivot for the counting pawl 163, which actuates the ten-tooth ratchet 164 fixed to a Geneva gear 165 mounted at 166 for rotation upon the outer face of the plate 153.

A forty-tooth gear 168 is rotatably mounted at 169, the teeth of which are adapted to be engaged at intervals by the single tooth 170 of the Geneva gear 165.

Referring to Fig. 2, it will be seen that the counting finger 158, which extends into the area of station C, is in the path of the rouleau 67 when it is carried by the turret from station B to station C. Therefore, as the rouleau is thus moved to station C, the counting pawl slide 156 by reason of the finger 158, is caused to be moved to the right, while the pawl 163 actuates the ratchet 164 and its associated Geneva gear 165, the ratchet being thereby advanced tooth by tooth in a clockwise direction of rotation. Means for returning the counting finger 158 to operating position after each movement to the right have been provided, in the following manner.

A three-fingered cam 198, Fig. 2, is fixed to the turret shaft 21 for rotation therewith, said rotation being intermittent, as previously recited. The position of the cam 198 on the turret shaft is substantially coplanar with the counting finger 158, shown in Figs. 9 and 10. As indicated on Fig. 1, the three-fingered cam is provided with a collar 199, through which means may be applied for fixing the cam to the turret shaft, such as the set screw 200.

Coplanar with the cam 198 is the substantially horizontal counting finger retrieving arm 201, pivotally mounted at 202 to the lower face of the turret bracket extension which carries the platen pressure bar 122. As shown in Fig. 2, the retrieving arm 201 extends in irregular form from the pivotal point 202 to the counting finger 158, the said arm being provided at its free end with a projection 203 which bears against a side of the counting finger 158. Fig. 2 shows the counting finger in position to be acted upon by a rouleau 67, having been brought to this position by reason of a cam point 204 bearing against the side of the retrieving arm at 205 as the cam is rotated by the turret shaft 21. Actually, this position of the counting finger 158, retrieving arm 201, and cam 198, as shown in Fig. 2, is attained immediately upon the initial movement of the coin turret 24, so that by the

time the rouleau at station B reaches station C, the counting finger is in the path of the rouleau, to move the said finger to the right and actuate the Geneva gear 165 through the counting pawl and ratchet 163-164. As the counting finger 158 is moved to the right, the retrieving arm 201 is moved back about its pivot 202, a clearance being provided upon the retrieving arm at 203 to preclude interference with the cam point 204. Since the counting finger 158 offers no resistance within the limits of station C, the rouleau is free to fall through the discharge ports 98-99. The counting finger 158 remains in the inoperative position during the three-second pause, and again assumes the position in Fig. 2 immediately upon the beginning of the one-third revolution of the coin turret 24, being carried there by the retrieving arm projection 203 by reason of the action of the cam 193 upon the retrieving arm.

The ratio between the Geneva gear 165 and the forty-tooth gear 168 being two to one, the Geneva gear tooth 178 will move the gear 168 a distance of two teeth, or one-twentieth of a revolution, upon each rotation of the Geneva gear.

Upon the assembly plate 153, below the gear 162, is mounted a pillow block 171, through which is slidably and rotatably mounted the counter setting shaft 172, said shaft extending beyond each end of the pillow block. Fixed near the inner end of the setting shaft 172 is the cut-off rod housing 173 including a longitudinally apertured vertically extending arm 174. The cut-off rod 175 is slidably mounted for vertical reciprocation in the arm 174, being provided with suitable means for precluding rotation, such as the pin 176 extending through the cut-off shaft and into the vertical slots 178 provided in the upper face of the vertical arm 174. Near the upper end of the cut-off rod 175 and laterally extending therefrom is the cut-off bar 179 which operates to cut off the electric switch 154 and stop the machine when a predetermined number of rouleaux have been acted upon, as will be explained later in detail. The cut-off bar 179 may be fixed to the cut-off rod by means of screws 177.

The cut-off rod 175 is normally urged upward by suitable means, such as the compression spring 180 in encircling relation with the cut-off rod, said spring abutting the lower face of the cut-off bar 179 and the upper face of the vertical arm 174. Upward movement of the cut-off rod may be limited by means of a stop pin 181 inserted transversely through the cut-off rod near its lower terminus, said pin abutting the lower face of the vertical arm 174, as shown in Figs. 9 and 10, when the cut-off rod 175 is in normal extended position.

The outer face of the gear 168 is provided with a series of abutments or slightly extending pins 182, 183, and 184, arranged in spaced circles concentric with the axis of said gear, each circle having a different number of abutments or pins. An inwardly extending pin 185 is provided on the cut-off rod 175, near its upper terminus. The inner face of the pin 185 is normally maintained in abutment with the outer face of the forty-tooth gear 163, Fig. 10, by suitable means, such as the spring 186, Fig. 9, fixed to the inner end of the setting shaft 172 and acting upon the vertical arm 174. The setting shaft, near its outer end, may be provided with a series of notches 188, 189, 190, 191, the last named notch

being for the purpose of setting the counting mechanism in neutral or non-operative position, this position being shown in Figs. 2, 9, 10 and 11. The notches 188, 189, and 190 are spaced 5 apart in correspondence with the concentric circles of pins 182, 183, and 184.

The setting lever 172 may be maintained in proper adjusted position by any suitable means, such as the setting latch 192, shown in perspective in Fig. 11. The setting latch is pivoted to the outer edge of the counter plate 153, as at 10 193, for free pivotal movement thereon, and may be provided with an extension 194 for the purpose of increasing the gravity of the latch as 15 it rests in a selected setting shaft notch.

As hereinbefore related, the number of pins 20 in each concentric circle differs. In the exemplified form, pins 182 in the outer circle are ten in number, equally spaced, or one pin for every four teeth on the gear 163. The pins 183 in the adjacent circle are four in number, equally spaced, or one pin for every ten teeth in the gear 168, while the smallest circle contains only 25 two pins, diametrically opposed, one for each twenty teeth. No pins are provided in the neutral portion of the gear 168.

The package counter may be set to open the electric switch 154 to stop the machine when any predetermined number of rouleaux have been 30 acted upon, these numbers in the exemplified case being twenty, fifty, and one hundred.

Assuming that the operator wishes to have the machine imprint twenty rouleaux of one 35 denomination, he first sets the gauge plate 49 to the proper elevation for the selected denomination by means of the stop block 59 in the manner hereinbefore recited. He then manually turns the setting shaft 172 counter-clockwise, as viewed in Fig. 10, by means of the setting 40 lever 195, against the force of the spring 189, until the latch 192 becomes disengaged from the setting shaft notch with which it is engaged, and pushes the setting shaft in until the latch 45 192 is in line with the notch 188. The setting lever is then released and the latch 192 permitted to gravitationally engage the notch 188. The face of the cut-off rod pin 185 will now be in abutment with the outer face of the forty-tooth gear, in the direct path of the pins 182, 50 being maintained in this position by spring 189.

The motor 43 may then be energized by moving the switch arm 195 to the substantially horizontal position shown in Fig. 9, to be acted upon by the cut-off bar 179 which it contacts. If the 55 machine has previously been used for imprinting rouleaux of fifty or one hundred lots, it may be necessary to set the counter manually in order to place the cut-off rod pin 185 in proper relation with one of the pins 182 for stopping the machine at the end of twenty imprints. This may be done 60 by manually reciprocating the counter pawl slide 156 by means of the counting finger 158, until one of the pins 182 contacts and depresses the cut-off rod pin 185 to the point where the switch arm 195 is depressed by the cut-off bar 179 to cut off the electric power and stop the machine. At this point the counting mechanism is set to 65 be automatically rendered inoperative at the completion of every twenty rouleaux imprints.

The operator then resets the switch and begins 70 feeding rouleaux to the turret at station A. The rouleaux are moved in succession to the imprint station B and the discharge station C, where each rouleau moves the counting finger 158 to the right, as viewed in Figs. 2 and 10. This move-

ment is translated to the Geneva gear 165 through the pawl and ratchet 163-164, to move the Geneva gear one-tenth of a revolution. When twenty rouleaux have passed through the discharge station C, the Geneva gear 165 has been rotated two complete revolutions, and the single tooth 170 thereon has moved the forty-tooth gear 168 for a distance of four teeth, which equals the distance between the pins 182. At this point a pin 182 will contact and depress the cut-off rod pin 185, moving the associated cut-off bar 179 downward to actuate the switch 154, thereby rendering the machine inoperative until the switch is again reset. If the rouleaux are discharged into a bag, as is common practice, the bag is removed from the hooks 100 and replaced with an empty one and the operation repeated. The machine now needs no resetting if rouleaux are to be imprinted in lots of twenty, since the pins 182 are in proper relation with the cut-off rod pin 185 for twenty-lot rouleaux of any selected denomination.

If rouleaux are to be imprinted in lots of fifty or one hundred, it may be necessary to reset the counting mechanism as hereinbefore related, in order to bring the cooperating pins in proper relation with each other before initiating operation on the first lot. It will be understood that the setting latch 192 should engage the setting shaft notch 189 for imprinting rouleaux in lots of fifty, and that the said latch will engage notch 188 for lots of one hundred. If an unlimited number of rouleaux are to be imprinted, the counting mechanism may be disposed in the neutral position shown in Fig. 9, with the latch 192 engaging the notch 191.

When the counter is set for lots of fifty rouleaux the Geneva gear 165 rotates five revolutions to move the gear 168 a distance of ten teeth before the electric switch 154 is actuated to stop the machine. By the same token, the Geneva gear rotates ten revolutions to move the gear 168 a distance of twenty teeth, or a half revolution, for breaking the electric circuit when the counter is set for lots of one hundred rouleaux.

It should be noted that the package counter is actuated only when a rouleau is carried to and discharged from station C. Regardless of the number of revolutions of the turret 24, therefore, only those rouleaux discharged at station C will be counted.

It will be understood, of course, that the gear ratios, timing, and package counter settings need not be those herein specified, since other ratios, timing and settings are possible within the spirit of the invention.

In conclusion it is to be understood that the device herein disclosed is but one of a number of possible arrangements or combinations of constituent parts that may be utilized in reducing the invention to a useful or practical form. Many of the machine parts are capable of considerable modification, and the substitution of various equivalents within the bounds of accepted engineering practice of machine design may be made within the scope of the appended claims, without departing from the spirit of the invention.

The machine may be provided with a suitable housing, not shown, for protecting the gears and other mechanism against the entry of dust and other extraneous matter, and for reducing physical hazards incident to the use of the machine. Such a housing, of course, would be provided with suitable openings for gaining access to the turret

and to the various operating levers during operation of the device.

What is claimed is:

1. A machine for marking an elongated rouleau which comprises a horizontal gauge plate, a printing wheel rotatably mounted above said gauge plate on a substantially vertical axis, means for advancing a rouleau along the gauge plate with the longitudinal axis of the rouleau disposed vertically, the lower end of the rouleau resting on the gauge plate, to a printing station adjacent the printing wheel, a back-up member spaced from the printing wheel and engaging the rouleau when at the printing station to hold the rouleau against the printing wheel, means for rotating the printing wheel, and means for bringing the printing wheel into engagement with the rouleau as the printing wheel turns to print indicia on the side of the rouleau.
2. A machine for marking elongated rouleaus which comprises a turret rotatable upon a vertical shaft, said turret having at least one upright open-ended rouleau-receiving socket adjacent the periphery thereof, a horizontal gauge plate disposed below the turret for supporting in upright position thereon a rouleau, the location of the plate being such that at least the upper portion of the rouleau is in said socket, drive means for turning said turret to shift the socket successively to a station in which a rouleau is deposited in said socket, a printing station and a discharge station, said drive means arresting rotation of the turret for a predetermined length of time when the socket thereof arrives at each of said stations, a printing wheel rotatably mounted at the printing station on a shaft substantially parallel to the shaft of the turret and outside the turret, said printing wheel engaging one side of the rouleau while the turret is arrested with the socket at the printing station, a pair of rotatably mounted back-up rolls inside the turret to engage the opposite side of the rouleau and hold the rouleau against the printing wheel, means for turning the printing wheel to cause the rouleau to turn between the printing wheel and the back-up rolls and means operating in timed relation with the drive means for withdrawing the printing roll and the back-up rolls from the periphery of the turret while the turret turns.
3. A machine for marking an elongated rouleau which comprises a turret rotatable upon a vertical shaft, said turret having a plurality of angularly spaced upright open-ended rouleau receiving sockets adjacent the periphery thereof, a horizontal gauge plate below the turret for supporting upright rouleaus in said sockets, the location of the plate being such that at least the upper portion of each rouleau is in one of the sockets, drive means for turning said turret to shift the sockets successively to a station in which rouleaus are deposited in said sockets to a printing station and a discharge station, said drive means arresting rotation of the turret for a predetermined length of time when one of the sockets arrives at each station, a printing wheel at the printing station mounted on an elongated shaft, said shaft being outside the turret and being substantially parallel to the shaft of the turret, said printing wheel engaging one side of the rouleau in the socket at the printing station, a pair of rotatably mounted back-up rolls inside the turret to engage the opposite side of the rouleau to hold the rouleau against the printing wheel, a driven bevel gear mounted on said shaft remote from the printing wheel, a main bevel gear in mesh with

the driven gear, the axis of the main bevel gear extending transversely of the shaft of the turret, means pivotally supporting the printing wheel shaft on the axis of the main bevel gear, means for holding the printing wheel and back-up rolls in engagement with the rouleau when the turret is at rest with one of the sockets at the printing station, means for turning the main bevel gear to drive the printing wheel and turn the rouleau between the printing wheel and the back-up rolls, and means operating in timed relation with the turret turning means for withdrawing the back-up rolls from the periphery of the turret and for swinging the printing wheel shaft around the axis of the main bevel gear and away from the periphery of the turret when the turret turns.

4. A machine in accordance with claim 3 characterized by the fact that the back-up rolls are mounted on a horizontally sliding carriage inside the turret, that the carriage is linked to the shaft of the printing wheel so that the rolls are withdrawn from the periphery of the turret when the printing wheel shaft is swung away therefrom, that means resiliently urge the carriage in a direction to bring the back-up rolls toward the periphery of the turret, and that the linkage contains a lost motion connection, whereby the back-up rolls and the printing wheel are both resiliently urged against the rouleau when the turret is at rest with one of the sockets at the printing station.

5. A machine in accordance with claim 3 characterized by the fact that the back-up rolls are mounted on a horizontally sliding carriage inside the turret, that the carriage is linked to the shaft of the printing wheel so that the rolls are withdrawn from the periphery of the turret when the printing wheel shaft is swung away therefrom, that means resiliently urge the carriage in a direction to bring the back-up rolls toward the periphery of the turret, that the turret includes a

downwardly extending peripheral skirt, and that the linkage contains a lost motion connection, whereby the back-up rolls and the printing wheel are both resiliently urged against the rouleau when the turret is at rest with one of the sockets at the printing station, the back-up rolls holding the rouleau against the skirt of the turret.

6. A machine in accordance with claim 3 characterized by the fact that the gauge plate is slidably mounted for vertical sliding toward and away from the turret and that means is provided for holding the gauge plate at predetermined elevations, whereby the printing wheel prints indicia on the rouleau at a predetermined height.

7. A machine in accordance with claim 3 characterized by the fact that the means for turning the main bevel gear is a driving bevel gear mounted on an axis substantially perpendicular to the axis of the printing wheel shaft and that a cam is attached to said driving bevel gear to turn with it, said cam engaging the support of the printing wheel shaft to swing the printing wheel shaft on the axis of the main bevel gear and away from the periphery of the turret when the turret turns.
